BATTERY TERMINAL CONNECTER

Albert H. Walde, Roxborough, Pa., assignor to
 Fox Automotive Products Corporation, Philadelphia, Pa., a corporation of Delaware

Application January 10, 1933. Serial No. 650,948

3 Claims. (Cl. 173—259)

My invention relates to battery terminal connectors and more particularly to the attainment of a very simple construction which is readily adapted for connecting electrical leads or cables 5 of different diameters as present in different ignition circuits, firmly to the terminal posts of the battery without the use of solder.

A further object of this invention is to provide a construction providing two integrally connected strap clamps, the free ends of the straps being provided each with a hole for the free passage of a single bolt therethrough, said bolt being threaded into and extending through a body portion of said connector, positioned intermediate 15 said straps and with which said straps are integral.

A further object of this invention is to provide a construction whereby the bared end of an electrical cable may be inserted into a substantially 20 cylindrical opening provided by a strap clamp and the free end of said clamp may be then drawn by a bolt or by a nut on said bolt to reduce the size of the hole in the connector by drawing the strap into tight engagement with the inserted 25 cable end whereby substantially the same pressure is brought to bear alike and evenly over the whole surface of the end of the cable inserted in said connector.

A further object of this invention is to provide 30 a connector which may be tightly, permanently clamped to the end of a cable by merely turning a single bolt therein and which may be afterward then tightly clamped to the terminal post of a battery by a single nut on the same bolt and 35 without turning the bolt; and which, conversely, may be clamped to a battery terminal by turning a single bolt thereof, said connector being also provided with a recess into which the bared end 40 of an electric cable may be thereafter inserted and firmly retained by merely turning the nut threaded over the same bolt.

Other objects of my invention will appear in the specification and claims below.

Referring to the drawing forming a part of this 45 specification and in which the same reference characters are employed throughout the various views to designate the same parts,

Fig. 1 is a plan view of the top of my improved connector;

Fig. 2 is a side elevational view of the construction shown in Fig. 1;

Fig. 3 is a bottom plan view of the same but with the bolt positioned reversely to that shown in Figs. 1 and 2;

Fig. 4 is an end elevation of the device shown

in the preceding figures looking into the sockets of the two strap clamps embodied therein; and

Fig. 5 is a cross-sectional view longitudinally of the bolt;

Figs. 6 and 7 illustrate further modifications of the invention.

My improved battery terminal connector consists primarily of a relatively thick block or body portion 1 which lies between the substantially parallel to the free ends of two strap 65 clamps 2 and 3 respectively. The strap clamp 2 is preferably integral with the block 1 and comprises the strap 4 which is of substantially circular form and of which the free end 4^a extends generally parallel with the one side 1^a of the block 70 1, the said free end being preferably of heavier construction than the circular portion of the strap 4 and being provided with an opening 5 for the free passage therethrough of a bolt 6 having a head 7 and a nut 8.

The block or body portion 1 is also provided with a hole 9 which is screw-threaded and in which the threaded portion of the bolt 6 fits.

Extending outwardly from the upper surface of the block 1 is the strap 10 of the clamp 3 and this strap is also provided with a thickened free end 11 through which extends a hole or opening 12 for the free passage therethrough of the said bolt 6.

The strap clamp 2 thus provides therethrough 85 a circular opening 13 which is of a diameter to snugly fit over the terminal post of a storage battery. Said battery posts are generally cylindrical in shape and of a standard diameter. They are sometimes slightly conical, but my invention 90 is equally adaptable to such conical terminals, it being only necessary to make the hole 13 of a taper to fit such tapering or conical post. The size and shape of the opening 13 through the clamp 2 is made to closely fit around a given 95 standard terminal.

The opening 14 in the clamp 3 is preferably of a size to receive the largest cable ordinarily used in the electric ignition systems of automobiles and the inner surface 11^a of the free end 11 100 thereof is preferably disposed at a slight angle to the adjacent side 1^a of the block or body portion 1 so that when drawn towards the block 1 the surfaces 11^a and 1^a will approach parallelism moving about the axis of the opening 14 of the 105 clamp 3. The end 11^a is normally spaced at a sufficient distance from the block 1 to enable the free end 11^a to be drawn sufficiently to substantially reduce the diameter of the opening 14 110 therein to fit securely around and firmly retain

a cable having a diameter substantially smaller than the actual diameter of the original normal hole 14 and thereby accommodate and firmly clamp the smallest of the standard cables employed in ignition circuits for automobiles.

Because it is desirable to protect the bared end 15^a of the cable 15 from the corrosive action from the fumes and acid of the battery, I preferably practically close the end of the opening 14 nearest the terminal with a wall 16 which may be provided with a substantially angular cut or slot 17 the opposing surfaces 17^a and 17^b of which are coincident with the corresponding surfaces 1^a of the block 1 and the surface 11^a of the free end 11, the apex of said angle being at or about the axis of the cylindrical opening 14 of the strap clamp 3. By virtue of this construction the cut is almost closed, when the clamp 3 is tightly drawn around the end of a cable of average diameter.

The manner in which my improved connector is used should now be apparent. As assembled in Figs. 1, 2 and 5, the bolt 6 is slipped through the hole 12 of the clamp 3 and is threaded into the hole 9 until the head 7 contacts with the outer surface of the free end 11 of the strap clamp 3. The bared end 15^a of the cable 15 is inserted into the hole or recess 14 of the clamp 3. When the end of the cable bottoms on the wall 16 the head of the screw is turned to draw the free end 11 toward the block 1 thus reducing the diameter of the hole 14 and turning the bolt-head 7 and with it the bolt 6 to draw the strap 10 so tightly around the end of the cable that the latter cannot be withdrawn without loosening the bolt 6. This will substantially close the angular slot or cut 17 in the wall 16 and the end of the cable will be practically enclosed within the opening or socket 14 and protected from the corrosive fumes and liquids of the battery.

Because the opening 14 is substantially cylindrical, the clamping pressure and the attendant friction between the cable and the connector will be substantially evenly applied, and distributed over the entire surface of the inserted cable end 15^a. This is quite different from the pressure and friction attendant upon the use of a tapered socket and a tapered threaded sleeve heretofore used for connecting a cable to a terminal connector without the use of solder.

Having thus secured the connector to the cable, the connector, with the cable attached thereto may now be attached to the battery terminal by fitting the strap clamp 2 around the end of a battery terminal, threading the nut 8 over the end of the bolt 6 and turning the said nut to draw the free end 4^a of the strap 4 snugly around the terminal.

But the device is equally adapted for first attachment to the battery terminal by inserting the bolt 6 into the opposite end of the threaded hole 9. Thus by first inserting the end of the bolt 6 into the hole 5 of the end 4^a of the strap 4 and then turning the screw in the threaded hole 9 until the head 7 engages the outer surface of the end 4^a of the strap 4, the clamp 2 may be slipped over the end of the battery terminal and the bolt 6 turned by its head 7 until the terminal is tightly clamped in the strap clamp 2. Now at any time thereafter the bared end 15^a of the cable 15 may be inserted into the socket opening 14 and the nut 8 may be threaded over the end of the bolt extending through the hole 12, and turned to draw the strap 10 tightly around the cable end 15^a.

Thus it is that my improved connector can be

readily fixedly connected to either a battery terminal or to a cable by a single bolt by merely slipping the free end of the bolt through the opening in the free end of the appropriate clamp and threading it into the body portion and having been secured to the selected conductor the other clamp may be thereafter closed around another conductor by tightening the nut threaded over the same bolt, and without loosening the connection first made.

While my device is primarily designed to connect a cable lead to a battery terminal in the more or less standardized relationship, with the battery terminal vertically disposed, and the cable horizontally disposed, it is now clear that the strap 4 of the clamp 2 might be integrally connected to the top of the body 1 or the clamp 3 might be integrally connected to the end of the body 1 so that the terminal and cable would be disposed in parallel instead of transverse direction or for connecting any two other electrical conductors.

Thus referring to Fig. 6, the terminal clamp 2^b and the cable clamp 3^b may be parallel and extend from the same side of the block 1^b which is provided with a threaded opening 9^b into which is threaded the bolt 6^b from either direction depending upon which clamp is first to be securely clamped to an electric conductor. As in the other modifications the openings 5^b of the clamp 2^b and the opening 12^b of the clamp 3^b are smooth openings larger than the bolt and through which the bolt may freely slide.

In the modification shown in Fig. 7 the axes of the clamps 2^c and 3^c are also parallel, but the straps extend from opposite sides of the block 1^c. The holes 5^c and 12^c like the corresponding holes in the other modifications are of larger diameter than the bolt 6^c and is threaded into a threaded hole 9^c in the block 1^c.

Having thus described my invention, what I claim and desire to protect by Letters Patent of the United States is:

1. In an electric connector the combination with an intermediate metal block and two metal strap clamps integral therewith, each clamp comprising a metal strap member one end of each being integral of said block and extending therefrom in a substantially circular direction and terminating in stiff free ends extending longitudinally in substantially parallel planes and being provided each with a hole therethrough, said holes being in axial alignment, said block being provided with a screw-threaded hole therethrough in axial alignment with said holes in said straps, of a bolt passing freely through the holes in said straps and threaded into said hole through said block, and a nut on the free end of said bolt.

2. In an electric connector the combination with an intermediate metal block and two metal strap clamps integral therewith, each clamp comprising a metal strap member one end of each being integral of said block and extending therefrom in a substantially circular direction and terminating in stiff free ends extending longitudinally in substantially parallel planes, and being provided each with a hole therethrough, said holes being in axial alignment, said block being provided with a screw-threaded hole therethrough in axial alignment with said holes in said straps, of a bolt passing freely through the holes in said straps and threaded into said hole through said block, a nut on the free end of said bolt, and a wall integral with one of said straps of one of said clamps and substantially closing the one end of the other.

wise free passage through said clamp and provided with a slot therethrough in registration with the space between the surface of said intermediate block and the inner surface of the free end of 5 the strap of said clamp.

3. In a battery terminal connector the combination with an intermediate metal block, having a screw-threaded opening extending therethrough, of two strap clamps integral with said block and 10 having metal straps extending therefrom in a substantial circular direction, the free ends of

said straps being respectively on opposite sides of said intermediate block and in substantially parallel planes transverse to the axis of the said threaded hole in said block and provided with holes therethrough in alignment with the said 80 threaded hole, of a bolt freely passing through said holes in said straps and threaded into said hole in said block and a nut on the free end of said bolt.

CERTIFICATE OF CORRECTION.

Patent No. 1,937,612.

December 5, 1933.

ALBERT H. WALDE.

It is hereby certified that error appears in the printed specification of the above numbered patent requiring correction as follows: Page 1, line 64, for "the" read and; and that the said Letters Patent should be read with this correction therein that the same may conform to the record of the case in the Patent Office.

Signed and sealed this 26th day of December, A. D. 1933.

Richard Spencer

(Seal)

Acting Commissioner of Patents.
